J. O. TARDIF

RAIL JOINT

Filed March 14, 1924

FIG. 4. " 12 "

INVENTOR
J. D. Tardif
By C. J. Fetherstonhaugh
Attorney.

UNITED STATES PATENT OFFICE.

JOSEPH OMER TARDIF, OF QUEBEC, QUEBEC, CANADA, ASSIGNOR TO GEORGE FREDERICK KNIGHT, OF QUEBEC, CANADA.

RAIL JOINT.

Application filed March 14, 1924. Serial No. 699,236.

To all whom it may concern:

Be it known that I, JOSEPH OMER TARDIF, a subject of the King of Great Britain, and residing at the city of Quebec, in the Province of Quebec, in the Dominion of Canada, have invented a new and useful Rail Joint, of which the following is the specification.

The invention relates to a rail joint as described in the present specification and illustrated in the accompanying drawings that form part of the same.

The invention consists essentially of the novel features of construction pointed out broadly and specifically in the claim for novelty following a description in detail of an acceptable form of the invention.

The objects of the invention are to eliminate the vibrations due to the transverse splits in the lines of railway incident to the end to end meeting of the rail lengths, to economize in the matter of rail renewals; to minimize the cost of maintenance of rolling stock; to afford comfort to passengers in railway trains; and generally to provide an efficient and durable rail joint.

In the drawings, Figure 1 is a perspective view of the joint showing two meeting rails broken away.

Figure 2 is a perspective detail of a joint member.

Figure 3 is a cross sectional view of the joint members showing a rail in dotted lines.

Figure 4 is a side elevation showing one joint plate removed.

Like numerals of reference indicate corresponding parts in the various figures.

Referring to the drawings, the rail heads 1 and 2 are formed with the longitudinal slots 3 and 4 respectively cut into said heads thereof at the inner edges.

The joint plate 5 is formed with a head 6 fitting closely into the slots 3 and 4 and bridging the split 7 in the line of rail made at the meeting of the rail ends and completing the rail heads to take the wheel tires, so in passing over the split 7, there will be no break in the line of railway and consequently no sinking of the rail ends, with the consequent absence of vibration.

The head 6 of the joint plate 5 is an upward extension from the vertical section 8 of said joint plate for the greater part of the length of said section the latter projecting slightly beyond the head 6 at the

ends 9 and rising upwardly into said head 6 intermediate of the length thereof.

The vertical section 8 at its lower end extends into the outwardly projecting flange 10 extending over one side of the rail bases 11 and curved at 12 around the outer edge thereof having the spike slots 13 towards either end.

The inner edge of the flange 10, where it joins the vertical section 8, extends into the lug 14 abutting the rail webs 15. The flange 10 and section 8 are reinforced by the integral buttresses 16 and 17 at each end beyond the head 6, and in the centre by the wide hollow buttress 19 formed by an outward bulge of the metal of both flange and section and extending from the outer edge of said flange to the upper edge of said section immediately under the head 6 and forming an additional support for the latter from its inner edge to its outer edge. The square bolt holes 19^a are arranged in pairs between the central and end buttresses.

The joint or fish plate 20 on the opposite side of the rails is formed with the vertical section 21 extending into the flange 22 projecting over the other side of the rail base 11 and curved at 23 over the outer edge thereof having the spike slots 24 and 25 towards either end. The lug 26 is in line with the flange 22, abuts the rail webs 15 and the vertical section 21 is offset outwardly and upwardly at its upper end 27 and terminates in the inclined surface 28 flush with the rail heads 1 and 2 and bridging the split 7 at the outer edges of the rails.

The end buttresses 29 and 30 are integral with the section 21 and flange 22 and extend upwardly behind the offset end 27 and the central hollow buttress 31 is formed by an outward bulge of the metal of the section 21 and flange 22 and extend from the outer edge of the flange 22 to the extreme upper edge of the offset 27 and into the inclined surface 28. The round bolt holes 32 are arranged in pairs between the central buttress 31 and end buttresses 29 and 30 and the two joint plates 5 and 20 are joined through the oval bolt holes 33 in the rail webs 15 by the bolts 34 having the squared stem ends 34^a inside the heads 35 and the nuts 36 screwed on to the ends projecting from the round bolt holes 32 with suitable lock washers intervening.

It will now be seen that a secure fastening is provided for the rail ends in a line of railway, which can readily be secured to the foundation or bed, whether wood ties or otherwise as only slight modification is necessary to accommodate it to any road bed. The bridging of the split represented by the meeting rail ends at the inside and the outside leaves the actual rails free to expand and contract according to changes of temperature and to slide freely within their secure fastening and at the same time furnish a surface for the wheels to pass over the split without in any way breaking the line of rail and causing the same to sink at each rail end customarily due to the passing of the load. The headed joint plate in itself is a good provision for bearing the load at the rail ends, but reinforced by the bridging against the inner side of the rail heads, it becomes tantamount to a continuation of the line, thus avoiding the breaks and consequent jars and jolts and damage to rolling stock.

Further it may be pointed out that the central buttresses being hollow allow the ends of the rails at the joint considerable freedom

during expansion and contraction due to climatic conditions, as it will be noticed that the joint plates are secured to the tie beyond the rail bases and the bolts operate in elongated holes, therefore the friction at the ends of the bases is removed, as they are not in contact with the joint and it is at the ends that the friction is much greater than under the bolt portions.

What I claim is:

A joint comprising a joint plate formed at the upper edge as a splice bar fitting into corresponding slots in the meeting rails and crossing from rail to rail, said plate having a hollow buttress in the centre thereof enclosing the webs and bases of the rails at the split, and a joint plate on the opposite side having a corresponding buttress thereby leaving a clear space about the rail ends below the tread, said joint plates having flanges extending beyond the rail bases and formed with spike slots and bolt holes for the fastening bolts.

Signed at Quebec this 1st day of February 1924.

JOSEPH. OMER TARDIF.
